UNITED STATES PATENT OFFICE.

HARRY B. CURTIN, OF GRAFTON, WEST VIRGINIA.

DESIGN FOR A SOAP-CAKE.

SPECIFICATION forming part of Design No. 24,246, dated April 23, 1895.

Application filed February 19, 1895. Serial No. 539,012. Term of patent 14 years.

To all whom it may concern:

Be it known that I, HARRY B. CURTIN, a citizen of the United States, residing at Grafton, in the county of Taylor and State of West Virginia, have invented a certain new and original Design for Soap-Cakes, of which the following is a specification, reference being had therein to the accompanying drawings.

The design is shown in the accompanying drawings, in which—

Figure 1 is a perspective view, and Fig. 2 a cross section taken on the line 2—2 of Fig. 1.

The leading feature consists in a continuous groove extending horizontally entirely around the cake or bar about midway between its upper and lower faces. The upper face *a*

and the lower face *b* are approximately flat and the side faces *c* and the end faces *d* are approximately vertical, said end faces being rounded, as shown. The continuous groove *e* is semi-circular in cross section and extends entirely around the cake about midway between its upper and lower faces.

What I claim is—

The design for a cake of soap substantially as herein shown and described.

In testimony whereof I affix my signature in presence of two witnesses.

HARRY B. CURTIN.

Witnesses:

ADOLPHUS RIGHMIRE,
ERNEST ELIJAH PRICE.
